Patented Aug. 28, 1917.

UNITED STATES PATENT OFFICE.

HENRY SCHMIDT, OF COLLEGE POINT, NEW YORK.

PEN.

1,238,201.

Specification of Letters Patent. Patented Aug. 28, 1917.

Application filed October 2, 1916. Serial No. 123,311.

To all whom it may concern:

Be it known that I, HENRY SCHMIDT, a citizen of the United States, residing at College Point, in the county of Queens and 5 State of New York, have invented certain new and useful Improvements in Pens, of which the following is a specification.

This invention relates to improvements in pens and has for its object to provide an attachment for pens whereby a quantity of ink will be held adjacent the pen nib and gradually fed thereto.

Another object of the invention is to provide a capillary ink container arranged to 15 gradually feed the ink to a pen nib.

Still another object of the invention is to provide an adjustable ink holding attachment for pens.

With the above and other objects in view, 20 which will hereinafter be fully explained, I have invented the device illustrated in the accompanying drawings in which—

Figure 1 is an elevational view of a pen showing my invention attached thereto.

Fig. 2 is an elevational view of the device 25 detached from the pen holder.

Fig. 3 is a plan view of a blank showing how the device is formed and the various ink holding nibs secured together, and

Fig. 4 is a plan view of a modification of 30 the several ink nibs showing the different configurations of the surfaces whereby their capillary attraction is greatly enhanced, and showing the several nibs independent of one 35 another.

Like reference characters indicate like parts throughout the following specification and in the several views in the drawings in which 1 indicates a pen holder having a 40 writing nib 2. 3 is a collar adapted to fit on the end 4 of the holder 1 and is slidable thereon whereby the integral capillary device 5 may be adjusted to fit against any part of the nib 2 in order that the amount of 45 ink fed to the under part of said nib may be regulated for fine and heavy shading of the letters to be formed by the nib. The collar 3 and the ink holding nibs 6, 7, 8, and 9 are formed integrally from one piece of 50 sheet metal and folded so that the members 6 to 9 will lie one upon the other. The shank portion 10 of the members 6 to 9 is provided with bends 11 and 12 whereof a certain resiliency is given to the device 55 in order that the ink will be caused to flow

therefrom when the pen point 13 is pressed upon the surface upon which writing is to be done.

The nib member 6 is formed with an oblong recess 14 and its edges 15 and 16 turned down. The member 7 has its nib portion provided with transversely inclined corrugations 17. The member 8 has its nib portion 18 formed in the shape of a frog's backbone, while the nib end 19 of the member 65 9 is formed spear shaped. These four members when folded one upon the other, because of their various configurations, form a device having great capillary attractiveness whereby upon one dip into the ink will 70 cause it to attract and retain a considerable quantity of the fluid which will be gradually fed from one to the other and thence to the writing nib 2. By sliding the collar 3 up or down upon the lower end of the pen 75 holder a greater or less flow of ink on the nib 2 will be had because of the more or less resilient action of the nib 2 upon the nibs 6 to 9. It is to be understood that if a less quantity of writing fluid is to be required 80 one or more of the nibs 6 to 9 may be eliminated, however, I have found that the use of the four members as shown produce the best results where considerable writing or drawing is to be done. The shanks 1 are 85 formed integral with the edge 20 of the collar 3 and the nibs 6 to 9 are in no way attached to the nib 2 which may be removed from or replaced on the pen holder 1 at will without interference with the member 21. 90

The device may be attached to any style or shape of pen without in any way interfering with the nib or holder. If desired one or more of the nib engaging members,— which may be formed independent of one another, as indicated in Fig. 4,—may be used independent of the other members, each of them being provided with a flat extension point 22 engageable with the surface of the pen point 2 or with one another. 95 These members may be formed independent of one another if desired as indicated in Fig. 4 and may be used independently if only a limited supply of ink is required. In placing the members 6 to 9 upon one another they may be arranged in any manner desired, however, the arrangement as indicated in Fig. 2, produces very satisfactory results and holds enough ink to write nearly 100 one thousand words. 105 110

Having now described my invention, that which I claim to be new and desire to procure by Letters Patent is:—

1. In combination a pen holder and pen, 5 an ink retainer consisting of a plurality of nibs graduated in length whereby the points of each of said nibs may engage said pen.
2. In combination a pen holder and pen, 10 an ink retainer consisting of a plurality of nibs graduated in length whereby the points of each of said nibs may engage said pen, said nibs being nested together.
3. In combination a pen holder and pen, 15 an ink retainer consisting of a plurality of nibs graduated in length whereby the points of each of said nibs may engage said pen, said nibs being nested together, said nibs having variformed recesses whereby ink retaining pockets are formed therebetween.
4. In combination a pen holder and pen, 20 an ink retainer consisting of a plurality of nibs graduated in length whereby the points of each of said nibs may engage said pen,

said nibs being nested together, said nibs having variformed recesses whereby ink retaining pockets are formed therebetween and a common support to which said nibs are integrally connected. 25

5. In combination a pen holder and pen, 30 an ink retainer consisting of a plurality of nibs graduated in length whereby the points of each of said nibs may engage said pen, said nibs being nested together, said nibs having variformed recesses whereby ink retaining pockets are formed therebe- 35 tween, a common support to which said nibs are integrally connected and a cylindrical shank adjustably mounted on said holder to which said support is integrally connected.

In testimony whereof I affix my signature 40 in the presence of two witnesses.

HENRY SCHMIDT.
